UNITED STATES PATENT OFFICE.

WILLIAM N. WHITELEY, OF SPRINGFIELD, OHIO.

SHEAF-CARRIER.

SPECIFICATION forming part of Letters Patent No. 311,550, dated February 3, 1885.

Application filed November 22, 1883. (No model.)

To all whom it may concern.

Be it known that I, WILLIAM N. WHITELEY, of Springfield, in the county of Clark and State of Ohio, have invented new and useful Improvements in Sheaf-Carriers for Automatic Binders; and I do hereby declare that the following is a full and accurate description of the same, reference being had to the accompanying drawings, wherein—

10 Figure 1 is a perspective view of my improved sheaf-carrier attached to an automatic binder. Fig. 2 is a side elevation of the sheaf-carrier. Fig. 3 is a plan of the same.

A is the main wheel of the harvester, to which my improvement is attached, and B B are portions of the supporting frame-work upon which the elevator and the binding mechanism are mounted. C is the gear-wheel or ring attached to the main wheel A for the purpose of transmitting motion to the shaft D, whereby the operative mechanisms are actuated. These and other parts necessarily shown in the drawings are common to machines of this description.

25 The binding devices are attached and operated upon a metallic frame, E, which consists, essentially, of a post provided with two laterally-extended parallel hollow arms, the post being rigidly attached to the frame of the machine. Said binding devices are thereby securely retained in place and proper working relation to each other, independent of the exigencies which may cause the joints of the machine-frame to shift their relative positions.

30 It will not be necessary to describe any of the operative parts of the binder, because they are not concerned in this invention. A bar, F, is attached to the upper arm of the frame E by means of the braces G H, so that it is firmly held in position with relation to the said upper arm. The bar F serves several purposes in the organization of the binder; but the purpose which is concerned in this case is the support of the inner ends of the bars I J, 45 upon the outer ends whereof the sheaf-carrier, which forms the particular subject-matter of this invention, is supported.

The sheaf carrier and discharger consists of a rock-shaft, K, mounted in bearings upon the outer ends of the bars I J. Its outer end is turned outward to constitute a crank-arm, L, and it is operated and controlled by a hand-

bar, M, one end of which engages with said crank-arm, and the other is provided with a hand-hold in convenient reach of the driver or attendant. The fingers N are severally attached at one end to the rock-shaft K, and from thence they depend and curve around toward the binding-machine, terminating just below the tail-board O of said machine when the carrier is in normal position. A brace or stretcher bar, P, is laid across the backs of the fingers N at a proper point, and each finger is rigidly fastened to said bar. A brace, Q, is also laid obliquely across said fingers and extended to the crank-arm L, near its outer extremity, and this brace not only restrains the fingers from lateral sway, but causes them to swing with the rock-shaft when it is rocked by means of the rod M. When the gavels are bound by the binding mechanism and the bound sheaves discharged over the tail-board O, which drops to a level position for that purpose, they are received upon the fingers N and held there until such time as the driver chooses, when by pulling the bar he causes the fingers to recede from under said sheaves, and they are permitted to drop upon the stubble. Having discharged the accumulated sheaves the fingers are returned for another load.

To relieve the driver from constant attention to the bar M, a loop, R, is placed upon the frame, preferably upon the bar I, and the bar M passes through said loop as a guide for its forward end. Two stops, S T, are placed upon the under side of said bar, in proper location as to the loop R, to enable one of them to lock against said loop and hold the teeth down in normal position to receive the sheaves, 40 as described, and the other to lock in a contrary way against said loop to hold the fingers back, in the position of discharge, when for any reason it is desired that the fingers shall not receive the sheaves. A yielding stop, U, 45 is placed on the frame to arrest the crank-arm L when the gatherer has reached a proper normal position, and it is convenient to fashion said stop from a rod of steel, one end being securely bolted to the bar I and the other end being wound around the rock-shaft K as a bearing, and to gain length to impart greater elasticity is finally terminated by a hook-shaped rest, into which the crank-arm L may

be received and elastically supported. The supports for the rock-shaft are arranged at one end and at the middle, so that the other end and one edge of the carrier overhang the 5 supports, and therefore when the carrier-teeth are swung back the attendant may have free and unobstructed access to the operative parts of the binding-machine.

The carrier device, being attached to the 10 binding-machine wholly by the supporting-boxes in which the rock-shaft L turns, may be readily removed by detaching said boxes, or liberating said shaft from them, so that when 15 not wanted for use it may be removed from the machine or replaced when required with very little trouble.

Having described my invention, I claim as new—

1. The combination, with an automatic 20 grain-binder, of a rock-shaft supported from the main frame thereof, curved depending

fingers secured to said rock-shaft, and a stop, U, upon the frame for arresting the downward movement of said fingers.

2. The rock-shaft K and crank L, provided 25 with the depending fingers to constitute a swinging sheaf-carrier, combined with the elastic rest or stop U.

3. The rock-shaft K, provided with the 30 crank-arm L and curved fingers N, attached thereto, combined with the brace or stretcher rod P, and the brace-rod Q, to constitute a sheaf-carrier.

4. The frame E, and the bar F, attached 35 thereto and supported thereon by the braces G H, combined with the bars I J, attached to said frame and bar, as shown, and the swinging sheaf-carrier, as set forth.

WILLIAM N. WHITELEY.
